UNITED STATES PATENT OFFICE.

CHARLES W. HORTON, OF BELLE RIVE, ILLINOIS.

CONCRETE CONSTRUCTION.

842,447.

Specification of Letters Patent. Patented Dec. 7, 1909.

Application filed June 1, 1909. Serial No. 499,289.

To all whom it may concern:

Be it known that I, CHARLES W. HORTON, a citizen of the United States, residing at Belle Rive, in the county of Jefferson and State of Illinois, have invented certain new and useful Improvements in Concrete Construction, of which the following is a specification.

My invention relates to improvements in concrete construction, and the leading object of my invention is the provision of a cheap durable bridge of the character described which will be simple and easy of construction and will prove serviceable at all times.

Another object of my invention is the provision of a bridge having an elevated footpath which will be safe and secure at all times and will not be endangered by any sudden freshet.

With these and other like objects in view, my invention consists in the novel features of construction and combination of parts substantially as disclosed herein and as illustrated in the accompanying drawings which illustrate a bridge constructed in accordance with and embodying the principles of my invention.

Figure 1, is a side elevation of my complete device, and Fig. 2, is a cross-sectional view on the line 2--2 of Fig. 1.

In the drawings: the numeral 1, designates my improved bridge and ford roadbed construction consisting of the side walls 2 of the base, the tapering upwardly projecting bracing posts 3 formed on the exterior faces thereof, and the floor or road bed surface 5 formed on the side walls.

In the construction of my device I first form the walls 2 with their bracing posts 3, and to secure said posts and walls in position and prevent them from spreading or otherwise endangering the safety and solidity of the bridge, I employ the tie and brace rods 6 molded therein.

In the channel of the stream which my bridge spans, I construct the culvert or pipe 7 which may be formed of iron, concrete or any other suitable material, and the top of the side walls slopes upward with a gradual incline from the point above said culvert to the level of the road bed proper, the culvert being preferably placed at the center of the device and the roadbed sloping from the ends down to the middle, the purpose of which

will hereinafter be shown. To cheaply and at the same time strongly reinforce the side walls, I fill the space between them to within a short distance of the top with gravel, dirt, or other waste material of like character, as is shown at 8, Fig. 2. Resting on the side walls, I place the floor of the roadway proper, which may be formed of wood, or any other suitable material. In the preferred form, however, I form the floor 5, of concrete as is shown in the drawings, the concrete resting on the side walls and fitting in therebetween and being supported by the material used as a filler.

Stretching across from one bank of the stream to the other and resting on the bracing posts on the lower side of the stream I have provided a footpath, said path being throughout its length on the same level as the road proper. My bridge, as shown in the drawings, comprises the floor 9, formed of concrete and having the longitudinal brace rods 10, and being provided with the railing 11, to which and the flooring is secured the screen guard material.

From the foregoing description taken in connection with the drawings it will be seen that I provide a bridge which is particularly adapted for use over small streams which are subject to freshets, the central culvert being constructed of sufficient diameter to carry off the usual flow of water, while when due to a freshet or other unusual occurrence an abnormal amount of water is present, the extra amount of water will rise and flow over the low point in the floor of the roadway and pass down stream, the foot path by its location remaining free from and unaffected by the high water and affording a safe and agreeable means for crossing the stream.

It will be understood that my device is particularly adapted for use over small streams which can be crossed in time of low water by means of a ford, but which are dangerous to ford in time of high water, since my device being cheap and simple of construction can be readily set up at small expense and would consequently prove a paying investment for the users thereof.

It is dangerous to cross a ford in high water and the attempt is often attended with fatal results, but such is not the case when the water is flowing over the channel in the center of my roadbed, as the height of the

floor prevents so great an amount of water flowing over the same, a large part of the excess water being carried off by the culvert and the posts 3 on the lower side of the structure would serve to arrest and prevent vehicles or live stock from being washed away.

I claim:

1. In concrete construction, a culvert, a road bed formed thereover and having its sides and floor sloping downward from the banks of the stream to a point above the culvert, the lower portion of the road bed at the center thus affording an overflow outlet for the water and relieving the device of the strain to which it would be subject were there no outlet for the water except the culvert.
2. In concrete construction, a roadway formed with its sides and floor sloping downwardly from the end toward the center, a pipe passing laterally under said roadway, and means for laterally bracing the roadway.
3. In concrete construction, a culvert, a concrete road bed passing thereover and curved downwardly from the ends toward the center to provide an overflow outlet for water not carried off by the culvert, tapering posts formed thereon for bracing the

roadbed, and a footpath carried by certain of said posts.

4. In combination with a concaved concrete roadbed sloping downwardly from both ends toward the center and providing an overflow outlet for water not otherwise carried off, a pipe passing laterally therethrough, tie and brace rods secured therein, and pillars formed thereon having broad bases tapering toward the top, for bracing the roadbed against lateral strain.

5. In combination with a concaved concrete roadbed sloping downwardly from both ends toward the center and providing an overflow outlet for water not otherwise carried off, a pipe passing laterally therethrough, tie and brace rods secured therein, pillars formed thereon for bracing the roadbed against lateral strain, brace rods passing through the pillars, and means providing a level footpath secured to the tops of certain of said pillars, and guard rails carried by the said path.

In testimony whereof I affix my signature, in presence of two witnesses.

CHARLES W. HORTON.
